UNITED STATES PATENT OFFICE.

ROBERT S. WILLIAMS, OF IRVINE, KENTUCKY, ASSIGNOR OF ONE-FOURTH TO THOMAS A. CHRISTOPHER AND ONE-FOURTH TO FRANCIS J. STEVENS, OF IRVINE, KENTUCKY.

THREAD CHASING OR CLEANING TOOL.

Application filed February 21, 1925. Serial No. 10,931.

My invention relates to improvements in devices for either chasing or cleaning screw threads, and the device is intended primarily for use in connection with locomotive or other plugs. Heretofore, it has been customary to perform the work on the plugs, by means of a lathe, requiring considerable time in placing, centering, and cutting with a thread chasing tool. It is the object of my invention however to provide an extremely simple and inexpensive device which will perform the desired work in less time and with less trouble, about one-eighth of the time usually necessary with a lathe, being required when my invention is used.

With the foregoing in view, the invention resides in the novel subject matter hereinafter described and claimed, the description being supplemented by the accompanying drawings.

Figure 1 is an elevation of the invention with parts broken away.

Figure 2 is a sectional view on line 2—2 of Fig. 1.

Figures 3, 4 and 5 are detail sectional views as indicated by lines 3—3, 4—4 and 5—5 of Fig. 2.

Figures 6 and 7 are detail sections as indicated by lines 6—6 and 7—7 of Fig. 1.

In the drawings above briefly described, the numeral 1 designates a cup-shaped head which is preferably provided with a shank 2, said shank being adapted to be fixedly held in any suitable manner. At its open end, remote from the shank 2, the head 1 is provided with an outstanding annular flange 3 at right angles to the axis of said head, said flange having a stepped outer side, which side comprises inner and outer concentric steps 4 and 5, and an annular outwardly facing shoulder 6 at their juncture.

The flange 3 of the head 1 is provided in its stepped side, with radial guideways, and each of these guideways preferably consists of an inner radial groove 7 formed in step 4, an outer radial groove 8 formed in step 5, and a notch 9 connecting the two grooves. Die-carrying members are disposed in the guideways 7—8—9, and each of these members by preference comprises a rod 10 passing through the notch 9 and provided at its outer end with a flat rectangular head 11 which is slidable in the outer groove

8, the outer side of said head being flush with the step 5, while the inner side of said head is spaced from the bottom 12 of this groove. The last named side of the head preferably engages guide shoulders 13 formed longitudinally in the groove 8. Threaded or otherwise connected with the inner end of each rod 10, and slidably received in the inner groove 7, is a die 14, one edge of this die being in slidable contact with the bottom of the groove, while its opposite edge is flush with the step 4. By preference, a coiled compression spring 15 surrounds each rod 10 with one end in contact with the die 14 and its other end in contact with the outer end wall of the groove 7, so that the several springs exert their power to normally force the dies and their carrying-members inwardly.

A flat, circular, scroll or cam plate 16 rests upon the shoulder 5 and is rotatable about the shoulder 6. In the preferred form of construction, this plate is formed with cam slots 17 which receive portions of bolts or the like 18 connected with the heads 11, so that rotation of the scroll plate will simultaneously move all of the die-carrying members and the dies 14 inwardly or outwardly as occasion may demand. The bolts 18 may well be shouldered to prevent their heads from binding tightly against the scroll plate 16, and the nuts 19 of said bolts are received in the inner portions of the grooves 8, that is the portions of these grooves adjacent their bottoms 12. Opposite sides of these nuts preferably engage the parallel groove walls, so that said nuts are held against dislocation.

An annular cap plate 20 is secured by screws 21 against the step 4, the peripheral edge of this cap plate being by preference provided with a lateral flange 22 which surrounds the shoulder 6 and laps onto the inner portion of the scroll plate 16. Thus, the plate 20 holds the plate 16 in proper place and also retains the dies and their carrying members within the guideways. The two plates 16 and 20 jointly extend over all of these guideways, so that they are covered and thus protected against all sorts of foreign matter.

For turning the scroll plate 16, this plate is provided with an appropriate lateral handle 23, and to retain said scroll plate in any

- position to which it is adjusted, an appropriate pawl 24 may be mounted on the plate to engage any of a series of notches 25 in the peripheral edge of the plate 20. Preferably, the pawl 24 is slidably mounted between appropriate guide ribs or the like 26, is provided with a spring 27 which normally projects it, and is formed with a finger-piece 28 by means of which it may be retracted. 10 The screw 29 shown in Fig. 6 may well be employed to hold the pawl 24 properly positioned between the guides 26, the head of said screw being slidably received in a slot 30 in the plate 16. 15 By releasing the pawl 24 and turning the scroll plate 16 in the proper direction, the dies may readily be adjusted to the work and all material removed from such work will be caught in the recess 31 forming the interior of the head 1. This head is preferably provided with a plurality of openings 32 through which the material received therein may discharge.

It will be seen from the foregoing that an extremely simple and inexpensive, quickly and easily adjusted, rapid and efficient tool has been provided. Moreover, quick and easy changing of dies may be effected, as removal of the cap plate 20 will permit the dies 14, rods 10, and scroll plate 16 to be removed as a single unit. The dies may then be easily removed and others substituted.

As excellent results are obtainable from the construction shown, it may well be followed, but within the scope of the invention as claimed, modifications may be made.

I claim:—

1. A thread chasing or cleaning device comprising a circular head having a central recess, said head being provided with a stepped side at right angles to its axis, said stepped side comprising inner and outer concentric steps and an annular outwardly facing shoulder at the juncture of said steps; said head being formed with radial guideways in its stepped side leading to the aforesaid recess and each comprising a radial groove in the inner step, a radial groove in the outer step, and a notch connecting the inner and outer grooves; die-carrying members passing through the notches of the aforesaid guideways and having flat heads slidably received in the outer grooves, the outer sides of said heads being flush with the

foresaid outer step, a cam plate resting on said outer step and extending across the outer grooves, said cam plate being rotatable about the aforesaid shoulder and having cam slots, bolts passing through said cam slots and the aforesaid heads, said bolts having nuts on their inner ends disposed in said outer grooves and engaging the side walls of the latter whereby the nuts are held against removal, dies carried by the inner ends of the aforesaid die-carrying members and slidably engaging the walls of the aforesaid inner grooves, and an annular cap plate secured to the above-named inner step and extending over said inner grooves, said cap plate having its peripheral portion disposed in overlapping relation with the inner portion of said cam plate, whereby to hold the latter and associated parts in operative position.

2. A thread chasing or cleaning device comprising a circular head having a central recess, said head being provided with a stepped side at right angles to its axis, said stepped side comprising inner and outer concentric steps and an annular outwardly facing shoulder at the juncture of said steps; said head being formed with radial guideways in its stepped side leading to the aforesaid recess and each comprising a radial groove in the inner step, a radial groove in the outer step, and a notch connecting the inner and outer grooves; die-carrying stems passing through the notches of the aforesaid guideways and having heads slidably received in the outer grooves, dies carried by the inner ends of said stems and slidably positioned in the inner grooves, coiled compression springs surrounding said stems in the inner grooves and engaging said dies and the inner ends of the inner grooves, a cam plate resting on said outer step and extending across the outer grooves, the aforesaid heads having projections engaging cams of said plate, and an annular cap plate secured to the above-named inner step and extending over said inner grooves, said cap plate having its peripheral portion disposed in overlapping relation with the inner portion of said cam plate to hold the latter and associated parts in operative position.

In testimony whereof I have hereunto affixed my signature.

ROBERT S. WILLIAMS.
